UNITED STATES PATENT OFFICE.

VENEMON L. WALLACE, OF MURRAY, UTAH.

CANNING-BUCKET.

1,302,253.

Specification of Letters Patent. Patented Apr. 29, 1919.

Application filed January 8, 1919. Serial No. 270,196.

To all whom it may concern:

Be it known that I, VENEMON LARRY WALLACE, a citizen of the United States, residing at Murray, in the county of Salt Lake 5 and State of Utah, have invented certain new and useful Improvements in Canning-Buckets, of which the following is a specification, reference being had to the accompanying drawings.

10 This invention relates to buckets and particularly to the bail engaging ears of canning buckets.

In canning factories many canning buckets are used and these buckets have to be 15 nested one within the other. When buckets used in canning factories are nested together they are liable to stick together and sometimes it is necessary to use such force in disengaging the buckets from each other that 20 the buckets are badly damaged and almost torn apart before they can be separated. Furthermore, if these buckets are left inserted one within the other they are very liable to become sour and musty.

25 The general object of my invention is to provide means permitting the nesting of the buckets but at the same time preventing the outer surface of one bucket coming in intimate contact with the inner surface of the 30 other bucket and specifically to do this by providing a pair of ears on each bucket, the pair of ears on one bucket engaging the rim of the bucket into which the next bucket is inserted so as to support the buckets with 35 their surfaces in spaced relation.

A further object is to provide an ear which will reinforce the bucket at its rim and have good engagement therewith.

Other objects will appear in the course of 40 the following description.

My invention is illustrated in the accompanying drawings, wherein:—

Figure 1 is a side elevation of a pair of nested buckets provided with my improved 45 ears; and

Fig. 2 is a vertical sectional view of one of the ears.

Referring to these drawings, 10 designates 50 a bucket of any usual or suitable form, as for instance, a metallic bucket having a bead 11 at its rim. Riveted or otherwise attached to diametrically opposite parts of the bucket

are the ears 12 with which a bail 13 is connected. My invention lies in the particular construction of the ear. The ear 12 as illustrated particularly in Fig. 2, is formed of relatively heavy sheet metal stamped out to provide a body 14 and a lug 15 through which the bail 13 passes, the lug 15 being offset from the plane of the body 14 at 16 so as 60 to accommodate and extend beneath the bead 11. The lower edge of the body is formed with an outwardly projecting flange 17 which is preferably formed by bending the metal of the ear outward and then folding 65 it again inward so that the flange has two thicknesses of material. This makes the flange particularly strong and rigid. This flange is disposed about $1\frac{1}{4}$ " or any desired distance below the bead 11 and when the 70 buckets 10 are nested one within the other, the flange 17 of one bucket will rest upon the bead 11 of the exterior bucket so that the buckets are supported in spaced relation to each other and so that the exterior surface 75 of one bucket does not come in intimate contact with the interior surface of the other bucket while at the same time the buckets may be nested in the ordinary manner. This not only prevents sticking of the buckets together but also permits the air to circulate 80 between the buckets, thus preventing their becoming musty and sour.

While I have provided an ear of a particular construction for this purpose it will be 85 understood that the ears might be modified in many ways without departing from the spirit of the invention as defined in the appended claims.

I claim:—

1. A bucket having thereon oppositely disposed ears and a bail engaging the ears, each of the ears being provided with an outwardly projecting flange at its lower edge adapted to engage the rim of a bucket within which 95 the first named bucket is supported to thereby support the buckets in spaced relation.

2. A bucket of the character described having a bead at its rim and oppositely disposed ears attached to the bucket, each of said ears being outwardly offset at its upper end to extend around and above the rim, the lower edge of each ear being outwardly flanged.

3. A bucket of the character described hav-

ing a bead at its rim and oppositely disposed ears attached to the bucket, each of said ears being outwardly offset at its upper end to extend around and above the rim, the lower edge 5 of each ear being outwardly flanged, the flange being formed of two thicknesses of material.

In testimony whereof I hereunto affix my signature in the presence of two witnesses.

VENEMON L. WALLACE.

Witnesses:

F. R. ANDERSON,
R. M. LUDDEN.
